UNITED STATES PATENT OFFICE.

SUSIE A. MEDDAUGH, OF NORTH WHITE LAKE, NEW YORK.

DRENCHING-BOTTLE.

No. 893,183.

Specification of Letters Patent.

Patented July 14, 1908.

Application filed December 7, 1906. Serial No. 346,722.

To all whom it may concern:

Be it known that I, SUSIE A. MEDDAUGH, a citizen of the United States, residing at North White Lake, in the county of Sullivan, 5 State of New York, have invented certain new and useful Improvements in Drenching-Bottles; and I do hereby declare the following to be a full, clear, and exact description of the invention, such as will enable others 10 skilled in the art to which it appertains to make and use the same.

This invention relates to drenching bottles for use in administering medicine to horses and other stock, and the main object 15 of the invention is to overcome the disadvantages to be found in devices of this class now in use.

The present devices are one and all rendered unfit for use by reason of the fact that 20 it is practically impossible to clean them, the only possible means of access to the container for the medicine being through a much contracted neck.

In order to effectually avoid the undesirable features found in drenching bottles now 25 on the market, the container or body portion of the bottle embodied in my invention is formed entirely of glass and the open end of the container is not contracted but is of the 30 same width as its body portion. At its said open end the container is screw-threaded for the connection therewith of the larger end of a flared cap which is provided with a contracted neck portion with which is connected, 35 by means of screw threads, a discharge nozzle. The glass container being non-contracted and without lateral projections at its open end, may be readily cleaned and the same may be said of the flared cap 40 member. The flaring cap and the nozzle portions of the device are also of uniform thickness throughout so that no lateral projections or obstructions occur either interiorly or exteriorly of the container. The 45 surface of the device therefore offers no obstructions or abrasions to the hand of the operator or to the portions of the body of the animal with which it may come in contact, and the absence of obstructions and projections in the interior effectually prevents the 50 lodgment of any of the contents of the container within it.

The absence of projections and obstructions enables the retainer to be rinsed more 55 effectually when it is desired to clean it from matter which does not adhere tenaciously,

while at the same time the construction of the retainer in the easily separable parts provides for a ready and thorough cleansing when the parts are separated, as hereafter 60 more fully explained.

In the accompanying drawings: Figure 1 is a side elevation of a drenching bottle constructed in accordance with my invention, and, Fig. 2 is a detail vertical sectional view 65 through the same.

Referring more specifically to the drawings, the bottle is shown as comprising a container 5, a cap 6, and a nozzle 7. The container 5 is formed entirely of glass and is of the same 70 diameter from its bottom to its top, the upper end of the container being entirely open. Graduation marks 8 are made upon the container at proper points so that the quantity of liquid contained therein may be deter- 75 mined at a glance.

The outer surface of the container at its upper or open end is screw-threaded as at 9 and the cap 6, which at its lower end is of the same diameter as the open end of the container, 80 is correspondingly threaded as at 10 for connection with the container. This cap 6 is preferably formed of tin or other suitable metal and is gradually contracted toward its upper end to form a neck 11 which is exteriorly screw-threaded as at 12 for connection therewith of the nozzle 7. The said nozzle 7 is preferably of the same diameter throughout its entire length and has its end opposite its threaded end partially closed as 85 at 13, there being an opening 14, however, left in the said end for the discharge of liquid. To render the nozzle 7 easier to clean, the end 13 thereof is concavo-convex as clearly shown in Figs. 1 and 2. The confronting 90 ends of the lower section 5 and the cap section 6 are reversely shouldered and uniting threads formed on the shouldered portions, and the confronting ends of the cap portion 6 and nozzle portion 7 are similarly shouldered and threaded, so that as the parts are 95 united the outer and inner faces are all flush throughout, thus obviating any obstructions either within or without the container. This is a very important feature of the device and 100 adds materially to its value and utility.

From the foregoing description of the invention and from the drawings it will be obvious that the container may be easily and quickly filled without any danger of spilling 110 the liquid, by simply removing the cap 6 therefrom and that the container and also

the cap are very easily cleaned, not being contracted at their open ends.

A further very advantageous feature resides in the fact that no screw threads are 5 exposed to the action of the medicine.

What is claimed is:—

A container comprising a lower section open at one end and with its sides of uniform thickness throughout, a cap section flaring 10 toward one end and with its sides of uniform thickness throughout and corresponding in thickness to said lower section, and a nozzle section corresponding in diameter to the smaller end of said cap section and with one

end contracted to form a jet discharge, the 15 confronting ends of said several sections reduced to form annular shoulders spaced from their ends with the reduced portions interlapping and the shoulders interbearing whereby a retainer is produced formed with 20 detachable sections and without exterior or interior obstructions or projections.

In testimony whereof, I affix my signature, in presence of two witnesses.

SUSIE A. MEDDAUGH.
